UNITED STATES PATENT OFFICE.

LLOYD A. MARTINELLI, OF SAN FRANCISCO, CALIFORNIA.

PISTON-RING COMPRESSOR.

Application filed January 16, 1922. Serial No. 529,608.

To all whom it may concern:

Be it known that I, LLOYD A. MARTINELLI, a citizen of the United States, residing at the city and county of San Francisco and State of California, have invented certain new and useful Improvements in Piston-Ring Compressors, of which the following is a specification.

In assembling pistons into the cylinders of internal combustion engines, the piston rings providing a tight fit between the piston and cylinder must be compressed within their grooves in the piston to admit of the insertion of the piston within the cylinder. 10 Certain constructions permit of the insertion and removal of a piston from the upper open end of the cylinder, which opening is afforded by removing the cylinder head, while other constructions necessitate the removal 15 and insertion of the piston through the bottom of the cylinder, due to the integral head construction of the cylinder.

My invention provides what may be termed a universal tool for use in compressing piston rings for the insertion of a piston either downwardly through the open top of the cylinder or upwardly through the open bottom thereof. The present tool is adapted for use under different conditions 20 by changing the plane of the lever or handle members thereof relative to the adjustable compressing band. A further feature of the present invention is to provide a band providing a conical opening, and which is secured to the lever members through universal pivot connections whereby the minor adjustment and compression movement of the band is afforded, and which band is further provided with adjusting means affording a 25 construction whereby the same may be varied to enable its use in connection with pistons of different diameters.

With the above mentioned and other objects in view, the invention consists in the 30 novel construction and combination of parts hereinafter described, illustrated in the accompanying drawings, and pointed out in the claims hereto appended; it being understood that various changes in the form, proportion, size and minor details of construction 35 within the scope of the claim may be resorted to without departing from the spirit

or sacrificing any of the advantages of the invention.

In the preferred embodiment of the invention illustrated in the drawings—

Fig. 1 discloses a view in perspective of the invention.

Fig. 2 is a detailed broken sectional view of the preferred embodiment illustrating the same used in connection with a piston inserted downwardly through the open top of the cylinder.

Fig. 3 is a view similar to Fig. 2, with the invention employed in connection with a piston inserted upwardly into a cylinder through the open bottom thereof.

Fig. 4 is a fragmentary detail of the compression band, disclosing the major adjustment thereof.

In the drawings, wherein like characters of reference designate corresponding parts—1 indicates the cylinder of an internal combustion engine and 2 the piston inserted therein, which piston is provided with the usual expandable piston rings 3 mounted in grooves 4 in the surface of the piston.

My tool for compressing the piston rings 3 within their grooves 4 during the insertion of the piston 2 within the cylinder 1, 80 comprises a metallic band 5, circular in plan and flaring transversely from one edge to the other, providing a conical compression ring when assembled. The band 5 is preferably formed in two sections disposed at 85 adjacent ends in overlapping relation, one provided with spaced apertures 6 and the other with studs 7 for reception within the apertures, this construction affording a major adjustment for the band which is maintained by the nuts 8. The free ends of the two sections of the band 5, which normally lie in slight spaced relation, have radially projected therefrom, close to the edge of the band, affording the point of reduced diameter of the ring, suitable fulcrum studs 9, on which pivot the head members 10 disposed substantially parallel with the outer face of the band, the heads being held there-to by nuts 11.

12 indicate a pair of levers pivotally united, as at 13, and to the upper bifurcated ends 14 thereof are attached, through pins 15 disposed at right angles to the studs 9,

the lower ends of the heads 10, the pins 15 uniting the upper ends of the levers to the heads to enable the pivotal movement of the levers at any angle to the plane of the band 5.

This universal connection between the levers 12 and the band 5 enables the use of the tool with motors permitting the disposal of the levers at right angles to the plane of the band 5.

10 the ring, as in the case of motors having removable heads, or in motors necessitating the disposal of the levers in a plane parallel to that of the face of the ring, occasioned by the lack of room, as in the case of motors 15 wherein the pistons are movable through the crank case opening.

When a major adjustment is made in the diameter of the ring by positioning the bolts 7 in various pairs of apertures 6 and overlapping to a greater or less extent the segmental portions of the band 5, no projecting parts of the band remain to interfere with the free and efficient operation of the tool, as it will be observed that pins 9 are 25 fixed to the free ends of the band forming segments.

Regardless, whether the adjustment of the

segments be to afford a larger or smaller diameter of the band, the excess material is disposed in such manner as to protect the 30 same from injury and to render the tool easy of operation, imparting a normal spreading movement to the free terminal ends of the band or ring and without the excess material interfering with the use of the tool or its 35 operation within limited areas.

I claim:

A piston ring compressor comprising a pair of pivotally connected levers having at their jaw ends pivoted heads movable from 40 the plane of said levers into positions at a right angle thereto, and conversely; a flexible band consisting of a pair of co-operating sectors disposed at one end in overlapping adjustable relation, and a fulcrum connection 45 between the free ends of said sectors and heads, said fulcrum connections disposed in a plane at right angles to the plane of pivoted connection between the jaw ends and heads.

In testimony whereof I have signed my name to this specification.

LLOYD A. MARTINELLI
